INVENTOR
Charles P. Oakman,
By his attorney,
J. H. McConaughay.

UNITED STATES PATENT OFFICE.

CHARLES P. OAKMAN, OF CAMBRIDGE, MASSACHUSETTS.

GRATE BAR.

Application filed November 28, 1919. Serial No. 340,973.

To all whom it may concern:

Be it known that I, CHARLES P. OAKMAN, a citizen of the United States, residing at Cambridge, in the county of Middlesex and 5 State of Massachusetts, have invented certain Improvements in Grate Bars, of which the following description, in connection with the accompanying drawings, is a specification, like reference characters on the drawings 10 indicating like parts in the several figures.

This invention relates to grate bars of the type used in automatic stokers. A common commercial type of automatic stoker 15 comprises a series of segments or sections jointed together to form an endless grate which is driven at a slow but substantially uniform rate of speed. The sections or segments of this grate each consists essentially 20 of a bar that extends transversely of the grate and supports a series of grate bars or grate elements, the ends of the supporting bar being carried by suitable links. Usually the support consists of a dove-tail bar and 25 the grate bars themselves are each notched or grooved to slide longitudinally on this bar, the entire series of bars making up an individual segment or section and being held in place by master bars at the ends of each 30 section. A well known example of this construction is the Coxe stoker.

Whenever one of these grate bars becomes broken, it is necessary to stop the movement of the grate, remove the master bar, and 35 slide off the bars up to the broken member. The broken bar can then be removed and a new one substituted for it, after which the bars that have been removed are replaced in their original positions. It is obvious 40 that this operation consumes much time and it is especially objectionable because it requires the stopping of the grate.

The present invention has for its chief object to devise a grate bar which shall be 45 particularly adapted for repair purposes and which can be placed in its operative position while the grate is travelling. This bar will be hereinafter referred to as a "repair bar", although it is obvious that 50 it could also be used, if desired, as regular equipment.

The nature of the invention will be readily understood from the following description when read in connection with the 55 accompanying drawings, and the novel fea-

tures will be particularly pointed out in the appended claims.

Referring now to the drawings,

Figure 1 is an angular view of a part of a grate bar support on which are mounted 60 two grate bars constructed in accordance with this invention; and

Fig. 2 is a fragmentary vertical cross sectional view through one of the grate bars shown in Fig. 1 and its support. 65

The grate bar support 2 shown in the drawings is of the usual construction and consists of a relatively flat bar of a dove-tail shape in cross section. The regular grate bars are placed on this bar 2 by sliding them 70 longitudinally of the latter bar until substantially the entire length of the bar is filled up, after which the master bars are secured in place, thus retaining all the bars in their operative positions. Each bar 75 of the usual type consists of a single piece of metal and has the general shape of the bars B-B shown in Fig. 1. The bar provided by this invention consists of two parts 80 or sections designated as 3 and 4, respectively. The lower parts of these sections are notched, as indicated at 5 and 6, respectively, to fit over the opposite edges of the support 2, and the section 3 has an upper extension 7 that overlaps a similar extension 8 on the section 4. Holes are drilled 85 through these overlapping parts to receive fastenings 9 and 10 that serve to secure the two sections together in their operative positions. 90

Assuming now that a grate bar of the regular type has been broken and lies at an intermediate point in one of the travelling sections of the grate, it can be replaced without disturbing the adjacent grate bars 95 by knocking it out of the grate when it comes around to the forward part of the grate, next placing the sections 4 and 3 on the bar 2 in the positions in which they are shown in Figs. 1 and 2, and finally driving 100 two pins or nails 9 and 10 through the overlapping parts of these sections, thus securing them together and causing them to grip the dove-tail bar 2.

This entire repairing operation can be performed while the grate is travelling. The objection to which prior constructions of this character were open thus is entirely avoided. Attention is particularly called 105 to the fact that this advantage is secured by 110

making the grate bar in sections which can be placed in their operative positions on the support 2 by moving them transversely of the bar into the slot formerly occupied 5 by the broken bar. The peculiar shape of the meeting ends of the sections and the fact that the sections can be secured together simply by driving pins, nails, or similar fastenings through the holes in the over- 10 lapping sections, also contribute to this result.

What is claimed as new is:

1. A grate bar for repair purposes comprising two sections notched to engage the 15 opposite edges of a dove-tail grate bar support and having parts that overlap when so mounted on said support, and means for securing said sections together.

2. A grate bar for repair purposes comprising two sections notched to engage the 20

opposite edges of a dove-tail grate bar support and having parts that overlap when so mounted on said support, and pins extending through said overlapping parts and serving to secure them together.

3. In a grate, the combination of a transverse bar of dove-tail cross section for supporting a series of grate bars, and a grate bar mounted on said supporting bar and consisting of two sections, said sections being notched to engage respectively the opposite edges of said dove-tail bar, said sections having grate surfaces and having parts that overlap each other when so mounted on said supporting bar, and means for securing said overlapping parts together.

In testimony whereof I have signed my name to this specification.

CHARLES P. OAKMAN.
